UNITED STATES PATENT OFFICE.

ROBERT B. PUCKETT AND HARRY R. ABBOTT, OF ST. LOUIS, MISSOURI.

HEEL.

1,253,278.

Specification of Letters Patent. Patented Jan. 15, 1918.

Application filed January 12, 1916. Serial No. 71,618.

To all whom it may concern:

Be it known that we, ROBERT B. PUCKETT and HARRY R. ABBOTT, citizens of the United States, residing in the city of St. Louis and 5 State of Missouri, have invented new and useful Improvements in Heels, of which the following is a specification.

This invention relates to heels, and has for its object to provide a heel of a peculiar and 10 novel construction adapted especially for use in connection with an outer sole having a part of its heel-seat portion cut out as illustrated and described in a companion application filed of even date herewith. With 15 the above object in view, the invention comprises a heel having a tenon, or filling-piece, of smaller dimensions than the body of the heel and adapted to be received into an opening made in the heel-seat portion of the 20 outer sole.

Our invention is illustrated in the accompanying drawing, in which—

Figure 1 is a perspective view of our improved heel;

Fig. 2 is a plan view of an outer sole adapted to be used in connection with said heel; and

Fig. 3 is a longitudinal sectional view through the outer sole and heel in their as- 30 sembed relation.

Referring now to the drawing, the numeral 1 indicates a heel of the ordinary construction and 2 a tenon, or filling, secured on the upper side thereof, as by nailing. 35 The tenon or filling 2 has the shape of an ordinary lift, and for the sake of economy may be cut from ordinary leather-board, or it may be in the form of a pieced lift, or it may be made from wood, cork, paste, or any 40 other suitable and durable cheap material. The outer sole 3 is provided in its heel-seat portion 4 with an opening 5, which opening has the configuration of a lift but is somewhat larger in dimensions than the filling 45 or tenon 2. This opening, as described in our companion application referred to, is made by cutting a lift from the heel-seat portion of the outer sole. An edge portion 6 surrounds the opening 5, and a correspond- 50 ing edge portion 7 is provided on the top of the heel by the filling or tenon 2. These corresponding edge portions are of ample

width to permit the necessary securing of the heel-seat portion of the outer sole to the upper, and of the heel to the heel-seat portion of the outer sole. It is desirable that the opening 5 should be larger than the filling or tenon 2 to permit of the necessary adjustment of the heel to the correct position on the shoe, in the event that the opening in the outer sole should not correspond exactly with the relative position of the filling or tenon 2 on the top of the heel. In other words, by making the opening 5 larger than the tenon or filling 2 the necessity for 65 absolute accuracy in positioning said opening on the one hand, or said tenon, or filling, on the other, is obviated.

While we have referred specifically herein to the use of our invention in connection 70 with a leather heel, we wish it to be distinctly understood that the invention is equally applicable for use with heels made of material other than leather.

We claim:

1. An unattached heel formed in part of leather, and having a tenon in the form of a lift projecting above its upper side, and forming a unitary part of the heel, said tenon being of less dimensions than the body 80 of the heel, and of cheaper material than the leather portion thereof.

2. An unattached heel constructed in part of leather, and having a tenon in the form of a lift projecting from its upper side and 85 forming a unitary part of the heel, said tenon being of less dimensions than the body of the heel, and being inferior in value to a whole leather lift of the same dimensions.

3. In combination with an outer sole of 90 leather having a section of the shape and dimensions of a heel lift cut from its heel seat portion, and a heel secured thereto, having a tenon in the form of a heel lift mounted on its upper side and forming a unitary part of 95 the heel in its unattached state, said tenon substantially filling the space in the outer sole made by the removal of the said lift section therefrom.

In testimony whereof, we have hereunto 100 set our hands.

ROBERT B. PUCKETT.
HARRY R. ABBOTT.
